HOUSING FOR A CARTRIDGE MAGNETIC TAPE PLAYER OR SIMILAR ARTICLE

Gerhard Dietrich, Furth, Bavaria, Germany, assignor to
Max Grundig, Furth, Bavaria, Germany

Filed Nov. 26, 1965, Ser. No. 88,214

Claims priority, application Germany Aug. 25, 1965

Term of patent 14 years

(Cl. D26—14)

FIG.1

FIG.2

FIGURE 1 is a front view of the housing for a cartridge magnetic tape player or similar article embodying my new design; and

FIGURE 2 is a perspective view of FIGURE 1 showing the front, top and the right end panels of the enclosing casing. The left end panel is substantially a mirror image of the right end panel, and the rear panel of the casing is substantially plain and unornamented.

The end panels of the apparatus casing are slightly inclined to each other as shown in FIGURE 1, and the front panel is surrounded by a trim strip of uniform width along the top and of a smaller uniform width along the bottom, the two end portions of the trim strip being tapered from top to bottom as shown in FIGURE 2. The front panel of the casing is provided with a cassette-receiving opening formed in the upper edge portion thereof, of which edge portion is grooved horizontally, said cassette opening being displaced nearer to one end panel

than the other, and a control knob is located within the longer upper edge portion of the front panel.

I claim:

The ornamental design for a housing for a cartridge magnetic tape player or similar article, as shown and described.
